UNITED STATES PATENT OFFICE.

JOHN W. KUNZLER, OF PITTSBURG, PENNSYLVANIA.

DESIGN FOR A CONDUIT.

SPECIFICATION forming part of Design No. 27,287, dated July 6, 1897.

Application filed March 13, 1897. Serial No. 627,432. Term of patent 14 years.

To all whom it may concern:

Be it known that I, JOHN W. KUNZLER, a citizen of the United States of America, residing at Pittsburg, in the county of Allegheny and State of Pennsylvania, have invented a certain new and useful Design for Glass Conduits, of which the following is a specification, reference being had therein to the accompanying drawings.

10 This invention relates to a certain new and original design for conduits for electric wiring and the like, of which the following is a specification, reference being had to the accompanying drawings, forming a part thereof.

15 Figure 1 is a perspective view showing one end of a section of my design, and Fig. 2 is a similar view of the opposite end.

The leading features of my design consist in the conduit *a*, being rectangular in cross-section, having a groove *b* on its one end and 20 an annular flange on its opposite end.

Having described my invention, what I claim as new, and desire to secure by Letters Patent is—

The design for a conduit as herein shown 25 and described.

In testimony whereof I affix my signature in presence of two witnesses.

JOHN W. KUNZLER.

Witnesses:

H. C. EVERET,
GEO. B. PARKER.
